UNITED STATES PATENT OFFICE.

BENJAMIN VAN RAALTE, OF NEW YORK, N. Y., ASSIGNOR TO E. & Z. VAN RAALTE, OF NEW YORK, N. Y., A CORPORATION OF NEW YORK.

VEIL.

1,163,287.

Specification of Letters Patent.

Patented Dec. 7, 1915.

Application filed December 24, 1914. Serial No. 878,835.

To all whom it may concern:

Be it known that I, BENJAMIN VAN RAALTE, a citizen of the United States, and a resident of the city, county, and State of New York, have invented a certain new and useful Improvement in Veils, of which the following is a specification.

The object of this invention is to provide a veil which can be securely attached to the hat without the use of pins or any like means of attachment; which will not disturb the trimming on the hat in any manner when placed on the hat or removed, and which may be readily adjusted without removal. My improved veil is also constructed so that it is not necessary to remove the same when the hat is being taken off, and it is also not necessary to remove the veil from the hat when a different arrangement of draping the veil is desired. These and various other improvements are carried out by my invention, a more particular description of which will appear below.

In the drawings appended hereto, Figure 1 is a plan view of my improved veil; Fig. 2 is a sectional view on the line 2—2 of Fig. 1, looking in the direction of the arrows, the elastic being shown in a stretched or extended position; and Fig. 3 is a perspective view of my improved veil as applied to a hat and in use.

My improved veil consists of a flat section of material of substantially square or rectangular outline 1. Veils made in this form can be made with a minimum amount of cost or expense as is not the case with circular, bag shaped veils where considerable time and material are wasted in forming the same. Furthermore, veils of square, or like outline, procure the pleasing arrangement of draping as shown herein.

Arranged approximately in the center of the veiling 1 is an opening 2, although if desired the opening may be positioned at any spot on the veil. Secured to the edge of the opening 2 is a strip of elastic material 3 attached to the veiling by a series of stitches 4. This elastic strip 3 is secured to the veiling in an extended or stretched con-

dition, so that when the same relaxes to its normal condition, a series of plaits 5 is formed in the veiling. It is necessary that the elastic be secured to the veil in a stretched condition and these plaits be in the surface of the veiling, else when an attempt should be made to attach the veil to the hat the veiling adjacent the opening 2 would distort and rip.

From the foregoing my invention will be readily understood. To place the veil upon the hat, it is merely necessary to enlarge the opening 2, by means of the elastic 3 surrounding said opening and pass the crown of the hat through said opening, so that the veiling will be arranged on the hat as shown in Fig. 3, the contraction of the elastic strip 3 holding the veil securely to the hat. To remove the hat it is not necessary to entirely remove the veil as is the case with ordinary veils, the elastic holding the veil securely to the hat under all circumstances. Also, if desired, the arrangement of draping the veil can readily be changed as desired without removing the veil from the hat.

With the ordinary type of veil, which is secured to the hat by pins or other like fastening means, when a change in the draping arrangement is desired, it is necessary to entirely remove the veil and re-attach the same, this operation being repeated until the veil has been draped as desired. With my improved veil, it is merely necessary to distract the opening 2 and twist the veil on the hat until the veil is draped as desired. Thus, if it is desired that any of the points 6 of the veil be at the front of the hat, at the rear, or at any other place, on the hat, this arrangement can be easily performed, without the necessity of removing the veil and changing its position until it has been arranged as desired.

Having thus described one embodiment of my invention, it is obvious that the same is not restricted thereto, but is broad enough to cover all structures that come within the scope of the annexed claim.

What I claim is:

An article of the class described compris-

ing a veil formed from a single section of a substantially flat piece of netted material, said section being substantially square in outline, an opening formed in said section at the center thereof and a strip of elastic material secured to the edge of said opening.

Signed in the city, county and State of New York, this 23 day of December, 1914.

B. VAN RAALTE.
